MOTOR-DRIVEN COMPRESSOR

Richard T. Cornelius, Minneapolis, and Nelson F. Cornelius, Anoka, Minn.

Application July 16, 1951, Serial No. 236,986

14 Claims. (Cl. 230—187)

1

The herein disclosed invention relates to multiple stage compressors of the type having a crank case with horizontally disposed radial cylinders communicating therewith and particularly to the oiling system therefor, and has for an object to provide an oiling system by means of which sufficient lubrication may be procured for all of the pistons.

Another object of the invention resides in equalizing the pressure on both sides of the low pressure piston during the suction stroke whereby oil may enter the space between the cylinder and piston and blow by the piston.

An object of the invention resides in providing a source of air under pressure at a pressure higher than the maximum atmospheric pressure at which the compressor is to be used and in connecting the intake of the low pressure cylinder to said source of air.

A still further object of the invention resides in constructing the compressor with a crank case having a crank case chamber and with cylinders communicating therewith and in providing a conduit connected to said source of air and to the crank case chamber.

Another object of the invention resides in constructing certain of the cylinders with enlargements adjacent the crank case and in providing cross heads in the enlargements of the cylinders with universal connections between the cross heads and pistons whereby oil entering the cylinders may drain into the enlargements and back into the crank case.

An object of the invention resides in the specific construction of the universal connection between the cross heads and pistons.

Another object of the invention resides in arranging the outlets for the cylinders at the lower portions of the same and in running conduits from the outlet of one stage to the inlet of the following stage whereby oil accumulating in one cylinder collects at the bottom thereof and drains into the outlet and the conduit connected thereto and is carried along with the air discharged from the one cylinder to the following cylinder.

A still further object of the invention resides in constructing the first cylinder of uniform bore so that oil entering the same may flow past the piston.

Another object of the invention resides in providing a construction whereby the oil is prevented from completely flowing from the oil receptacle and into the crank case in the event of the compressor being operated at an angle or completely overturned.

2

A still further object of the invention resides in providing an oiling system in which a vent is provided for discharging air into the crank case to allow the oil to drain back into the oil reservoir and in constructing said vent so that the same will remain open regardless of the position of the compressor.

Another object of the invention resides in providing an oil receptacle contacting the crank case and adapted to be urged into engagement therewith by means of a spring to which the receptacle is attached and which in turn is secured to the oil pump.

Other objects of the invention reside in the novel combination and arrangements of parts and in the details of construction hereinafter illustrated and/or described.

In the drawings:

Fig. 1 is an elevational view of a compressor illustrating an embodiment of the invention.

Fig. 2 is a plan sectional view taken substantially on line 2—2 of Fig. 1.

Fig. 3 is an elevational sectional view taken on line 3—3 of Fig. 2.

Fig. 4 is a fragmentary elevational sectional view taken on line 4—4 of Fig. 3.

Fig. 5 is a fragmentary elevational sectional view taken on line 5—5 of Fig. 2.

Fig. 6 is a fragmentary elevational sectional view taken on line 6—6 of Fig. 5.

Fig. 7 is a fragmentary elevational sectional view taken on line 7—7 of Fig. 3, and drawn to a greater scale.

Fig. 8 is a fragmentary elevational sectional view taken on line 8—8 of Fig. 3 and drawn to a greater scale.

In the drawings has been shown a multiple stage high pressure compressor capable of pumping 3,000 lbs. pressure per square inch and of relatively light weight so that the same may be installed on an airplane. This compressor comprises a crank case having three cylinders attached thereto and extending radially outwardly therefrom in a horizontal direction. Above the crank case and supported thereon is an electric motor having a vertical shaft extending into the crank case chamber and having attached to it within said chamber crank means. The other end of the motor shaft has attached to it exteriorly of the motor a fan which blows air downwardly past the motor and the compressor to cool the same. At the lower end of the crank case is provided an oil receptacle having a pump therein for delivering the oil into the crank case chamber. The low pressure cylinder is of uniform

bore and has mounted in it a piston of uniform diameter. The higher pressure cylinders have enlargements at their inner ends. In the higher pressure cylinders are pistons which are connected by means of universal connections to cross heads slidably mounted in the enlargements. These cross heads are connected to and operated by the crank means. The inlet to the low pressure cylinder is connected to a source of air under pressure, the pressure of which is above the atmospheric pressure at the lowest altitude at which the compressor is to be used. A conduit connects the crank case chamber with said inlet so that the crank case pressure is equalized with respect to the inlet pressure. On the suction stroke of the low pressure piston oil is hence drawn into the low pressure cylinder, past the piston and into the compression chamber thereof. The outlets from the higher pressure cylinders are on the bottom thereof and the inlets on top and conduits are connected from the outlet of one cylinder to the inlet of the other. By means of this construction the oil leaking past the low pressure piston is successively passed through the various high pressure cylinders. As it travels the oil passing by the pistons therein is drained back into the crank case, thus lubricating all of the pistons. The lower portion of the crank case has secured to it an oil pump which is driven from the crank pin and which delivers oil into the crank case chamber. This pump is disposed below the crank case and is received in an oil receptacle which is removable and which engages the crank case to form a fluid-tight connection therewith. A spring secured to the pump has attached to it a nut into which is screwed a screw engaging the oil receptacle. By means of this construction the oil receptacle is yieldingly held in engagement with the crank case. To procure ready return of oil to the receptacle an air vent is provided which communicates at one end with the crank case chamber. The other end of this air vent communicates with the interior of the receptacle through an annular passageway encircling a funnel in which the oil discharged into the crank case chamber is received.

The compressor of the invention utilizes a crank case 10 constructed with side walls 11 and 12, and a front wall 13. The upper portion of the case 10 has a wall structure 16 serving a purpose to be presently described and the lower portion is open and surrounded by a flange 17. This crank case has a crank case chamber 15 within the same and into which certain of the moving parts of the compressor are disposed.

Mounted on the upper portion of the crank case 10 is an electric motor 18. This motor comprises a core 19 disposed in a tubular housing 20. Screws 21 extending through the housing and screwed into the core hold the same attached to the housing. On the core 19 are windings 221 which produce the magnetic field for the motor. The core 19 is formed with a bore 22 in which is rotatably mounted an armature 23. This armature has a core 24 in which are wound windings 25 connected to a commutator 26. Since motors of the class shown are well-known in the art the motor has not been shown in detail. The armature 23 has an armature shaft 27 which is rotatably supported at its lower end in a bearing 28 mounted in a socket 29 formed in the lower end of a boss 30 forming part of the wall structure 16 and which serves as the lower end bell for the motor. The upper end of the shaft 27 is journaled in a bearing 31 which is similarly

mounted in a bore 32 formed in an end bell 33 mounted on the housing 20. This end bell has an annular recess 34 in which the housing 20 is received and a flange 35 forming part of the wall structure 16 is likewise formed with a recess 36 in which the lower end of the housing is received. Issuing outwardly from the end bell 33 are lugs 38 through which bolts 39 extend. These bolts are screwed into corresponding lugs 37 issuing outwardly from the flange 35. By means of this construction the parts are rigidly clamped together.

Mounted on the wall 13 of crank case 10 is a low pressure cylinder 40 best seen in Fig. 2. This cylinder is formed with a flange 251 which overlies the wall 13 and is secured thereto by means of screws 252. Cylinder 40 has a bore 45 in which is mounted a liner 41. This liner in turn has a bore 43 in which is slidably positioned a piston 42. The said liner and the inner end of the cylinder 40 extend through an opening 44 in the wall 13 of crank case 10 so that the interior of the cylinder 40 is in direct communication with the chamber 15 in the crank case 10. The bore 45 of cylinder 40 is formed with an enlargement 46 at its outer end which forms a shoulder 76 against which a flange 247 formed on the liner 41 is seated. The outer end of the liner 41 forms a valve seat against which a disc valve member 47 is seated which is best shown in Fig. 5. This valve member has lugs 48 projecting outwardly from its edges which engage the enlarged portion 46 of the bore 45 and guide the disc for axial movement. This construction also provides air passages 49 between the lugs 48 through which the compressed air may pass in leaving the cylinder. This disc 47 is held in engagement with the end of the liner 41 by means of a compression coil spring 50 which is seated against a cup-shaped member 51. This member is bolted by means of a bolt 53 to a plate 52 which covers the open end of the cylinder 40. Plate 52 is attached to the cylinder 40 by means of screws 54.

The end 55 of armature shaft 27 has attached to it a crank 56 which is formed with the usual crank pin 57. This pin has a ball bearing 58 mounted on it and which is also mounted in a boss 59 integral with a connecting rod 60. This connecting rod is pivoted by means of a wrist pin 61 to the piston 42. Rotation of the shaft 27 causes the connecting rod 60 to be operated and the piston 42 to be reciprocated in the usual manner.

The inlet to the cylinder 40 is to one side of the cylinder as shown in Fig. 2 and consists of a threaded boss 62 in which is screwed a fitting 63. This fitting has screwed into it a T 64, one leg of which is attached to a nipple 65 adapted to be connected to a source of air under pressure. The said T is further connected to a tube 66 which in turn is connected to a fitting 67 tapped into the wall 13 of the crank case 10. By means of this construction the chamber 15 of crank case 10 is brought in communication with the inlet to the low pressure cylinder and the pressure in said crank case chamber equalized with the pressure in the cylinder proper during the suction stroke of the piston 42. The inlet 62 is in communication with an annular groove 68 formed in the cylinder 40 and which communicates with a number of ports 69 formed in the liner 41. These ports permit air to enter an annular space 70 encircling the piston 42 intermediate the ends of the same. The piston 42 has

a valve 71 formed in the head of the same and air entering the space 70 may pass through passageways 72 in the piston 42, past the valve 71 and into the space 73 at the head of the piston. The piston 42 on its pressure stroke compresses the air in the chamber 73 forcing it past the valve member 47 and into a chamber 74 formed in the enlargement 46 of the bore of the cylinder. As best shown in Fig. 5 a fitting 75 is screwed into a boss 77 formed on the cylinder 40. This fitting has connected to it an elbow 78 which in turn is connected to a tube 79 leading to the intermediate pressure cylinder 80.

The intermediate pressure cylinder 80 is similar to the cylinder 40 and has a flange 81 overlying the wall 84 of crank case 10 and secured thereto by means of screws 82. The said cylinder, as best shown in Fig. 3, is formed with a bore 83 having an enlargement 84 at its outer end and another enlargement 85 at its inner end. In the cylinder proper is mounted a liner 86 which is constructed similar to the liner 41 of cylinder 40 and which is mounted in position therein in the same manner. This cylinder has a disc valve 87 at the outer end of the liner 86 similar to the valve 47 which is held in engagement with the end of said liner by means of a compression coil spring 88. This spring is seated against a plug 89 screwed into the end of the cylinder 80. Within the liner 86 is mounted for reciprocating movement a piston 90. In the enlargement 85 of bore 83 is mounted a liner 91 which has a flange 92 on the same clamped in between the flange 81 and the wall 84 of the crank case. In this liner is slidably mounted a cross head 93 which is formed with an end wall 94. This end wall has a circular hole 95 in the same and which communicates with a slot 96 extending through said end wall and through the cross head proper as best shown in Fig. 4. In the piston 90 is formed a groove 97 which serves as a throat and which receives the portion of the end wall 94 of cross head 93 adjacent the hole 95 and connects the two parts together. By means of this construction the piston is universally connected to the cross head. The cross head 93 is connected to a connecting rod 98 by means of a wrist pin 99. This connecting rod in turn is connected by means of another wrist pin 100 to lugs 101 formed on the boss 59 of the connecting rod 60. By means of this construction the cross head 93 and the piston 90 are simultaneously reciprocated and the piston 90 floats within the liner 83 of cylinder 80 so that no lateral strains are placed upon the same so that an extremely tight fit may be made between the piston and the liner. An inlet fitting 102 is screwed in a boss 103 formed on the cylinder 80 at the upper portion of the same. This inlet communicates with a port 104 formed in the liner 86 and which in turn communicates with the chamber 105 formed at the head end of the piston 90. The fitting 102 has connected to it an L 106 which in turn is connected to the tube 79 leading from the cylinder 40. The outer end of the cylinder 80 is formed with a boss 107 which is threaded to receive a fitting 108. This fitting has secured to it an L 109, best shown in Fig. 1, and which is connected to an outlet tube 110. The fitting 108 communicates with a passageway 111 which in turn communicates with the chamber 112 formed in the enlargement 84 of the bore 83.

The tube 110 is connected to an elbow 116 which in turn is connected to an inlet fitting 113 of the high pressure cylinder 114. This cyl-

inder is constructed similar to the cylinder 80 excepting that the same is of smaller dimensions and that piston 115 of the same is of smaller diameter. The said piston is connected to a cross head 117 which is slideable in a liner 118 similar to the liner 91. A connecting rod 119 connects the cross head 117 to a wrist pin 120 which is mounted in lugs 120 formed on the boss 59. The cylinder 114 has an outlet fitting 121 to which a suitable conduit may be connected and which leads to the reservoir in which the compressed air is maintained. Another outlet 253 is employed into which a nipple 254 is screwed and which is connected to a pressure switch gage or similar device. Due to the similarity of the cylinder 114 and the cylinder 80 and associated parts, the description thereof will not be repeated though it can be readily comprehended that the construction conforms to that illustrated in connection with the cylinder 80.

Lubrication of the moving parts of the compressor is procured from oil indicated at 122 and contained within an oil receptacle 123. This receptacle has a spheroidal bowl 124 at the lower portion thereof and a cylindrical portion 125 above the bowl. The cylindrical portion terminates in an upwardly extending sleeve 126, best shown in Fig. 7, which fits over the flange 17 of crank case 10. An O-ring 127 forms a tight connection between said sleeve and flange.

The lowermost portion of the case 10, as previously described is open and is closed by means of a cover 128. This cover is screwed to the flange 17 by means of screws 129. The cover 128 has a funnel 130 cylindrical in form depending therefrom and which has a bottom 131. Issuing upwardly from the bottom is a partition 132 which provides at its upper end a bearing 133 for a vertical shaft 134. Partition 132 has a bore 135 forming a passageway within the same and which is open at the bottom and communicates with the interior of the receptacle 123. The funnel 130 has a chamber 136 within the same and which communicates through openings 137 in the partition 132 with the bore 135 and thus communicates with the interior of the receptacle 123. Extending downwardly from the funnel 130 is an arm 138 which supports a gear pump 139. This gear pump has a case 140 in which the gears 142 of the pump are disposed. The shaft 134 is journaled in a bearing 141 formed in the pump case 140 and has attached to it one of the gears 142 of the gear pump. The inlet to the gear pump consists of an opening 146 in the case 140 which is in communication with the bowl 124 of the receptacle 123 and the oil 122 in which the pump is immersed flows directly into this hole and into the pump proper. The outlet of the pump discharges through a passageway 143 in a tube 147 connected to case 140 and forming part of partition 132 and is discharged through a nozzle 144 extending above the cover 128 and discharging upwardly against the crank structure including the crank 56 and the associated parts.

For the purpose of directing air into the crank case chamber 15 a vent is employed which is constructed as follows: Encircling the funnel 130 is a ring 148. This ring is formed with an annular groove 149 forming in conjunction with the outer surface of the bowl an annular passageway. As shown in Fig. 7, the partition 132 is formed with a tube 150 which has a passageway 151 communicating with the passageway 149 on one side 75 of the funnel. On the other side of the funnel

130 the ring 148 is formed with an outlet 152 which discharges into the interior of the receptacle 23. By means of this construction air is directed from the receptacle 123 through the passageways 149 and 151 and into the chamber 15 to vent the receptacle 123.

The shaft 134 is driven by means of a flanged bushing 153 which has a slot 154 formed in the same. A pin 155 issuing downwardly from the crank pin 57 is received in this slot. The shaft 134 is axially disposed with reference to the motor shaft 27 and rotation of the pin 155 serves to drive the gear pump 139.

The receptacle 123 is held attached to the case 10 by means of the following construction best shown in Figs. 3 and 7. The pump 139 is secured together by means of bolts 182. These bolts also attach to the pump case 140 a leaf spring 156. This spring is formed with a horizontal lower reach 157 which has secured to the center of the same a nut 158. A screw 159 extends through the bowl 124 of receptacle 123 and screws into the nut 158. This screw has a hand wheel 160 by means of which the same may be rotated and a washer 161 which engages the inner part of the bowl 124 holds the said screw from disengagement from the bowl. When the screw 159 is engaged with the spring 157 the bowl is resiliently urged against the case 10 of the compressor and thus secured from movement to form a fluid-tight connection with the case.

To prevent loss of oil from the crank case 10 and outwardly past the bearing 28 the following construction is employed. The shaft 27 has a reduced portion 55, previously referred to, and which is journaled in the bearing 28. Also mounted on this reduced portion is an oil slinger 162 which consists of a web 163 having holes 164 in the same. This oil slinger has a hub 165 which fits on the reduced portion 55 of the shaft 27 and is held in place thereon by suitable means not shown. Depending from the web 163 is a flange 166 which fits closely to a turned portion 167 formed in the boss 30. These parts fit close enough to prevent the free passage of oil past the slinger and yet are not so tight but what the compressor may rotate freely. Extending across the space between the hub 165 and flange 166 is a screen 168, a felt disc 169 and another screen 170. A snap ring 171 holds the parts in position. Any oil discharged by the slinger 162 is collected by grooves 172 formed in the boss 30 and drains back into the crank case chamber 15. Above the oil slinger 162 is mounted a conventional oil seal 173. This seal comprises a flexible annular member 174 held against a collar 175 by means of a cage 176 and a compression coil spring 177. This spring is seated against a floating collar 178 which rides on a disc 179. By means of this construction oil is prevented from passing into the interior of the motor 18.

Cooling of the entire compressor including motor 18 is accomplished by means of a fan 248 which is attached to the upper end of the shaft 27. This fan is somewhat larger than the motor housing 20 and air is directed past the motor proper as well as against the same and reaches the various cylinders of the compressor to also cool the compressor. A guard 249 encloses fan 248 and is secured to the end bell 33 by means of screws 250.

The operation of the invention is obvious. In normal use oil is pumped by the pump 139 and

5 discharged through nozzle 144 into the crank case chamber 15. Here the oil is distributed to the various cylinders and the connecting rods and cross heads lubricated. Due to the crank case chamber being at the same pressure as the pressure in the air inlet, oil flows past the first piston on the suction stroke and into the air stream. The oil is then successively directed into the other cylinders and lubricates the same. Any oil blowing by the pistons in these cylinders drains back into the crank case chamber. The oil not picked up by the moving parts flows through funnel 130 and the holes 137 back to the oil receptacle. The oil in the chamber 15 is replaced by air taken from the crank case chamber 15 through the passageways 151 and 149. If the compressor becomes inverted the oil in the bowl 124 flows into the cylindrical portion 125 of receptacle 123 without flowing through the passageways 149 and 151. Inclination of the compressor does not plug the vent and prevent air moving in passageways 149 and 151.

20 The advantages of the invention are manifest. Lubrication is procured for the compressor and parts in a manner such that waste of lubrication is prevented. Lubrication will at all times be available regardless of the position of the compressor. Should the compressor be momentarily inverted the oil will flow from the bowl to the cylindrical portion without flowing out through the vent. Thus the crank case chamber is prevented from being flooded with oil. The vent being open to the oil receptacle on the side of the funnel opposite the opening thereof to the crank case chamber, flow of oil in the vent is greatly restricted.

25 Changes in the specific form of the invention, as herein described, may be made within the scope of what is claimed without departing from the spirit of the invention.

30 Having described the invention, what is claimed as new and desired to be protected by Letters Patent is:

35 1. In a multiple stage compressor a crank case having a crank case chamber, a low pressure cylinder and a higher pressure cylinder, both having their inner ends communicating with said crank case chamber, pistons in said cylinders, crank means within said crank case chamber pivotally connected to and operating said pistons, an oil receptacle, oil distributing means including a conduit extending between said oil receptacle and said crank case chamber for delivering lubricating oil from the oil receptacle to the crank case chamber the oil in said crank case chamber being splashed into the inner end of said low pressure cylinder and equalizing means communicating with and equalizing the pressure on both sides of said low pressure cylinder during the suction stroke thereof.

40 2. In a multiple stage compressor, a crank case having a crank case chamber, a low pressure cylinder and a higher pressure cylinder both horizontally disposed and having their inner ends communicating with said crank case chamber, an oil reservoir, a cross head slideable in said higher pressure cylinder, a piston slideable in the same cylinder, a universal connection between said cross head and piston, a piston in said low pressure cylinder, means communicating with and delivering oil from said oil receptacle to said low pressure cylinder and discharging the same into the pressure chamber of the low pressure cylinder, a discharge conduit between the bot-

75

tom of said low pressure cylinder and the inlet to said higher pressure cylinder and directing oil passing by the low pressure piston into the higher pressure cylinder and past said higher pressure piston and cross head and back into said crank case.

3. In a compressor, a crank case having a crank case chamber, a cylinder communicating therewith, said cylinder having a concentric enlargement adjacent said crank case, a piston disposed in said cylinder and forming therewith a pressure chamber, said piston having an annular groove in the same at the end thereof nearest said crank case and forming a throat therein and a flange at the end of the piston, a cross head disposed in said enlargement of the cylinder, said cross head having an end wall and a skirt slidable in said enlargement, said end wall having a circular hole therein concentric with the piston and of a diameter to receive said throat, said end wall having a slot therein extending through said skirt and said skirt having an opening communicating with said slot and through which said flange may be directed whereby the piston and the cross head may be assembled by relative transverse movement therebetween.

4. In a compressor, a crank case having a chamber therein, a cylinder having its inner end communicating therewith, a piston in said cylinder, crank means in said crank case pivotally connected to and operating said piston, said crank case being open at the bottom, a closure attached to the lower end of the crank case, a funnel formed on said closure and extending below the same, an oil pump mounted on said funnel and disposed below the same, means forming a passageway between the outlet of the pump and the crank case chamber, an oil receptacle attached to the lower portion of said crank case and receiving said funnel and pump, said funnel having a passageway at the lowermost portion thereof communicating with and directing oil entering the funnel back into the receptacle, a ring encircling said funnel and having an annular passageway therein and being formed with an opening on one side of the funnel and an air duct having a passageway connected to said annular passageway on the other side of the funnel, said duct extending upwardly beyond the uppermost portion of the funnel.

5. In a compressor, a crank case having a chamber therein, a cylinder having its inner end communicating therewith, a piston in said cylinder, crank means in said crank case pivotally connected to and operating said piston, a funnel at the lower portion of said crank case having an opening at the top communicating with and receiving the oil discharged into said crank case chamber, an oil pump disposed below said funnel, means forming a passageway between the outlet of the pump and the crank case chamber, an oil receptacle disposed at the lower portion of said crank case and receiving said funnel and pump, said funnel having a passageway at the lowermost portion thereof communicating with and directing oil entering the funnel back into the receptacle, a ring encircling said funnel and having an annular passageway therein and being formed with an opening on one side of the funnel and an air duct having a passageway connected to said annular passageway on the other side of the funnel, said duct extending upwardly beyond the uppermost portion of the funnel.

6. In a compressor, a crank case having a chamber therein, a cylinder having its inner end

communicating therewith, a piston in said cylinder, crank means in said crank case pivotally connected to and operating said piston, a funnel at the lower portion of said crank case having an opening at the top communicating with and receiving the oil discharged into said crank case chamber, an oil pump disposed below said funnel, means forming a passageway between the outlet of the pump and the crank case chamber, an oil receptacle disposed at the lower portion of said crank case and receiving said funnel and pump, said funnel having a passageway at the lowermost portion thereof communicating with and directing oil entering the funnel back into the receptacle, and means including an air duct extending between said crank case chamber and the space within said receptacle, said duct having an opening disposed above the uppermost portion of said funnel.

7. In a compressor, a crank case having a chamber therein, a cylinder having its inner end communicating therewith, a piston in said cylinder, crank means in said crank case pivotally connected to and operating said piston, a funnel at the lower portion of said crank case having an opening at the top and receiving the oil discharged into said crank case chamber, an oil pump disposed below said funnel, means forming a passageway between the outlet of the pump and the crank case chamber, an oil receptacle disposed at the lower portion of said crank case and receiving said funnel and pump, said funnel having a passageway at the lowermost portion thereof communicating with and directing oil entering the funnel back into the receptacle, said receptacle having a space above the passageway in the funnel leading to the receptacle of at least as great a volume as the volume in the receptacle below said passageway.

8. In a compressor, a crank case having a chamber therein, a cylinder having its inner end communicating therewith, a piston in said cylinder, crank means in said crank case pivotally connected to and operating said piston, a funnel at the lower portion of said crank case having an opening at the top and receiving the oil discharged into said crank case chamber, an oil pump disposed below said funnel, means forming a passageway between the outlet of the pump and the crank case chamber, an oil receptacle disposed at the lower portion of said crank case formed with a globular portion receiving said pump and with a cylindrical portion receiving said funnel, said funnel having a passageway at the lowermost portion thereof communicating with and directing oil entering the funnel back into the receptacle, said cylindrical portion having a volume at least as great as the volume of said globular portion.

9. In a compressor, a crank case having a chamber therein, a cylinder having its inner end communicating therewith, a piston in said cylinder, crank means in said crank case pivotally connected to and operating said piston, a funnel at the lower portion of said crank case having an opening at the top and receiving the oil discharged into said crank case chamber, an oil pump disposed below said funnel, means forming a passageway between the outlet of the pump and the crank case chamber, an oil receptacle disposed at the lower portion of said crank case formed with a globular portion receiving said pump and with a cylindrical portion receiving said funnel, said funnel having a passageway at the lowermost portion thereof communicating

with and directing oil entering the funnel back into the receptacle, said cylindrical portion having a volume greater than the volume of said globular portion.

10. In a compressor, a crank case having a chamber therein, a cylinder having its inner end communicating therewith, a piston in said cylinder, crank means in said crank case pivotally connected to and operating said piston, an oil pump supported by the crank case and disposed below the same and discharging into said crank case chamber, means for driving said oil pump from the crank means, an oil receptacle disposed below said crank case and engageable therewith and receiving said pump, a spring attached to said pump and disposed below the same, a threaded member carried by said spring and a complementary threaded member carried by said receptacle and engaging the threaded member on said spring to cause said spring to yieldingly act on said receptacle and to urge the receptacle into engagement with said crank case.

11. In a compressor, a crank case having a chamber therein, a cylinder having its inner end communicating therewith, a piston in said cylinder, crank means in said crank case pivotally connected to and operating said piston, an oil pump supported by the crank case and disposed below the same and discharging into said crank case chamber, means for driving said oil pump from the crank means, an oil receptacle disposed below said crank case and engageable therewith and receiving said pump, a looped leaf spring attached to said oil pump and having a portion extending transversely thereof and below said pump, a threaded member carried by the denoted portion of said spring and a complementary threaded member carried by said receptacle and engaging the threaded member on said spring to cause said spring to yieldingly act on said receptacle and to urge the receptacle into engagement with said crank case.

12. In a multiple stage compressor a crank case having a crank case chamber, a low pressure cylinder and a higher pressure cylinder, both having their inner ends communicating with said crank case chamber, pistons in said cylinders, crank means within said crank case chamber, connected to and operating said pistons, an oil receptacle adjacent said crank case, oil distributing means including a conduit extending between said oil receptacle and said crank case chamber, for delivering lubricating oil from the oil receptacle to the crank case chamber, the oil in said crank case chamber being splashed into the inner end of said low pressure cylinder, a conduit connected to and conducting air under a regulated pressure higher than the maximum atmospheric

pressure in which the compressor is to be operated to the intake of the low pressure cylinder and a conduit connected to and conducting air under like pressure to said crank case chamber.

5 13. In a multiple stage compressor a crank case having a crank case chamber, a low pressure cylinder and a higher pressure cylinder, both having their inner ends communicating with said crank case chamber, pistons in said cylinders, crank means within said crank case chamber pivotally connected to and operating said pistons, an oil receptacle, oil distributing means including a conduit extending between said oil receptacle and said crank case chamber, for delivering lubricating oil from the oil receptacle to the crank case chamber, the oil in said crank case chamber being splashed into the inner end of said low pressure cylinder, a conduit connected to and conducting air under a regulated pressure higher than the maximum atmospheric pressure in which the compressor is to be operated and to the intake of said low pressure cylinder, and a conduit connected to said first named conduit and to said crank case chamber.

20 14. In a multiple stage compressor a crank case having a crank case chamber, a low pressure cylinder and a high pressure cylinder, both having their inner ends communicating with said crank case chamber, pistons in said cylinders, crank means within said crank case chamber pivotally connected to and operating said pistons, an oil receptacle, oil distributing means including a conduit extending between said oil receptacle and said crank case chamber, for delivering lubricating oil from the oil receptacle to the crank case chamber, the oil in said crank case chamber being splashed into the inner ends of said low pressure cylinder, a fitting connected to and conducting air under pressure and to the low pressure cylinder and a conduit connected to said fitting and to the crank case and bringing the pressure in said crank case up to the pressure in said fitting.

45 RICHARD T. CORNELIUS.
NELSON F. CORNELIUS.
